(57) **CLAIM**

The ornamental design for an eyeglass, as shown and described.

DESCRIPTION

FIG. 1 is a front perspective view of the eyeglass of the present application;

FIG. 2 is a front elevation view thereof;

FIG. 3 is a rear elevation view thereof;

FIG. 4 is a right elevation view thereof;

FIG. 5 is a left elevation view thereof;

FIG. 6 is a top elevation view thereof;

FIG. 7 is a bottom elevation view thereof;

FIG. 8 is a front perspective view of the eyeglass of FIG. 1 without the ball marker shown in phantom in FIG. 1;

FIG. 9 is a front elevation view thereof;

FIG. 10 is a rear elevation view thereof;

FIG. 11 is a right elevation view thereof;

FIG. 12 is a left elevation view thereof without the ball marker shown in phantom in FIG. 5;

FIG. 13 is a top elevation view thereof; and,

FIG. 14 is a bottom elevation view thereof.

Phantom lining, where used, is for illustrative purposes only and is not intended to limit the claimed design to the features shown in phantom.

1 Claim, 10 Drawing Sheets
